4

FIG. 2

FIG. 1

FIG. 4

FIG. 3

FIG. 1 shows a front elevation view of my new and novel design for an eyelash curler;

FIG. 2 shows a side elevation view of my eyelash curler in the direction of lines 2—2 of FIG. 1;

FIG. 3 shows a top plan view of my eyelash curler as seen in the direction of lines 3—3 of FIG. 1; and

FIG. 4 shows a perspective view of my eyelash curler in the direction of lines 4—4 of FIG. 2.

The characteristic feature of my design resides in the particular curling head configuration shown.

I claim:

The ornamental design for an eyelash curler, as shown and described.
